Inventor:
Lester L. Bond

United States Patent Office.

LESTER L. BOND, OF CHICAGO, ILLINOIS.

Letters Patent No. 71,575, dated December 3, 1867; antedated November 15, 1867.

IMPROVEMENT IN HORSE HAY-FORKS.

The Schedule referred to in these Letters Patent and making part of the same.

TO ALL WHOM IT MAY CONCERN:

Be it known that I, LESTER L. BOND, of the city of Chicago, in the county of Cook, and State of Illinois, have invented certain new and useful Improvements in Hay-Forks; and I do hereby declare that the following is a full, clear, and exact description thereof, reference being had to the accompanying drawings, making a part of this specification, in which—

Figure 1 is a back view,

Figure 2 a front view,

Figure 3 a side view, and

Figure 4 a view of the rod or bar connecting the sliding shaft with the lever, detached.

Like letters refer to similar parts in all of the figures.

The nature and object of my invention consist in constructing a hay-fork, of the class known as harpoon-forks, so that when driven into a body of hay, two or more points can be turned out on opposite sides to take hold of the hay; in the novel construction and arrangement of the prongs and operating-mechanism connected therewith, as hereinafter more fully explained, so that in unloading from a wagon or other place where there is a floor, the fork can be sent to the bottom and the prongs pass under the very lowest hay or straw; in doing this by a peculiar arrangement and location of the joints; in a new arrangement of the lever, and in the several combinations hereinafter set forth and claimed.

To enable others skilled in the art to make and use my invention, I will proceed to describe its construction and operation.

The entire fork is made of iron, steel, or other suitable metal or material. I usually make it of wrought iron, with steel prongs, slightly tempered, though it may be entirely made of either material. The shaft A is about three and one-half feet long, and the upper end provided with a ring or hole. It is about three-fourths of one inch in width and seven-sixteenths in thickness. The lower end is provided with an open mortise for the insertion of the rods k k. The sliding bar B is about two feet and eight inches in length, and of the same width as the shaft A, and about five-sixteenths of an inch in thickness, the proportions being the same whether the size of the shaft is increased or diminished. Exact proportions in this respect, however, are not material. At the lower end of the shaft, and near the upper end of the bar B, are bands or sockets C, through which the sliding bar works. Into the open mortise, at the lower end of the shaft, I insert the rods k k, which are pivoted at l. These rods are about four inches in length, and of sufficient size to give the required strength. The length will depend somewhat upon the other parts, as they must correspond with the width of the head formed by the union of the prongs E E and the length of the rod c. The length of the rod c will not, however, control the length of these, as that will operate at almost any length, if not desired to turn half around. It will also be evident that the shaft A and the sliding bar B can be reversed, and the bar shown as the sliding bar made the shaft. In that case the operation of the lever D will be reversed, when it will be advisable to increase the length of the rod c, so that the lever will turn only one-fourth instead of half way around, as shown, and in that case the spring and catches may be dispensed with. The rods k are pivoted to the outer angle of the prongs E at m. The prongs E are about five inches in length from the highest to the lowest point, and about three and one-half from the lowest point to the angle at m. They are hinged together at n and to the sliding bar, and are ground sharp, or nearly so, from the lowest point to the angles at m, and one may be made a little shorter and fitted into the other, so as to prevent hay from getting between them. The pivots n and m are so arranged and located that a line from the two will be at an angle of about forty degrees with the outer line of the prongs E. A location at this angle will give a leverage both for opening and closing the prongs, and avoid any dead-points. The distance from n to m is about one and one-fourth inch, and the width of the head formed by the prongs is about two and one-fourth inches at the widest point. The sliding bar B is connected at the upper end to the lever D by the flat rod c, which is pivoted to it at i and to the lever at j. The flat rod or connection c is bent or made in form of a sector, in order to pass the joint or pivot k of the lever. The lever D is made somewhat smaller than the shaft A, and is about seven inches in length. Its upper end is provided with a ring or hole for a cord. Between this and the shaft there is a spring, a, provided with a catch or lock; or it may be made of a separate piece, provided with a spring, b, and the same lock or catch f. This lock or

catch will fasten the prongs of the fork in either an open or closed position. When open, it catches in a small hole, *g*, in the end of the sliding bar, and when closed, in a similar hole in the block or projection of the shaft attached for that purpose. The lever *D* is pivoted to the shaft at *h* and to the sector at *j*. The connection at *j* is made on the back side of the lever, (the front being the direction in which it turns,) so that when it is turned down to open the prongs, it becomes the central pivot between *h* and *i*, and forms an angle with them, so that when the lock or catch *f* is withdrawn by a suitable cord, the weight of the hay will throw the lever back, which it would not do with certainty if the three joints formed a line instead of an angle, as described. The joint or connection *i* is made in the middle of the sliding bar, as no advantage is gained by throwing it to one side to increase the angle. The spring-catch is withdrawn by a cord which is attached to it at *d*, and passes through the lever at *e*.

In operation, the fork is inserted in hay or straw by pressing down the shaft *A*. This pressure being divided upon the points *m m*, keeps the points of the prongs together; and the action of the hay or straw upon the incline of the prongs also assists in keeping them together, so that they never separate when being thrust down. When the fork is down, the lever *D* is then turned downwards, and the force required to open the prongs also carries the fork slightly downwards, so that there is scarcely any movement of the compressed hay, and the fork opens very easily; and the pressure to open being downwards, the fork is kept in place while being opened; and the lever being turned down, the fork can be drawn through a window or over a beam without catching or being discharged of its load. It is operated by a horse in the usual manner, the rope being attached to the ring of the shaft.

Hay-forks with a single point or prong have heretofore been known and used. I do not, therefore, claim turning a fork-prong broadly; but

What I claim as new, and my invention, and desire to secure by Letters Patent, is—

The prongs *E*, pivoted to the bar *B*, and connected by links *K* to the bar *A*, in combination with the lever *D* pivoted to the bar *A*, and connected by link *c* to the bar *B*, when said parts are arranged for joint operation, substantially as herein described.
